M. BRANDT

WASHING MACHINE

Filed Dec. 13, 1923

INVENTOR,
Max Brandt.
By Martin P. Smith ATTY.

UNITED STATES PATENT OFFICE.

MAX BRANDT, OF LOS ANGELES, CALIFORNIA.

WASHING MACHINE.

Application filed December 13, 1923. Serial No. 680,357.

To all whom it may concern:

Be it known that I, MAX BRANDT, a citizen of the United States, residing at Los Angeles, in the county of Los Angeles and State of California, have invented certain new and useful Improvements in Washing Machines, of which the following is a specification.

My invention relates generally to laundering appliances and more particularly to an apparatus that may be readily applied to an ordinary bath tub to form an efficient and practical washing machine.

The principal objects of my invention are, to provide a household laundering apparatus that is of relatively simple structure, capable of being easily and cheaply produced and constructed so as to be readily applied to or removed from an ordinary bath tub; to provide a laundering apparatus of the character described that may be folded up and packed into a relatively small space while not in use and further, to provide a household laundering appliance that is actuated by a small electric motor, whereby the laundering operation may be quickly and economically accomplished without any effort on the part of the operator, other than the transfer of the laundered articles from the tub to the wringer that is associated with and forms a part of my improved washing machine.

With the foregoing and other objects in view, my invention consists in certain novel features of construction and arrangement of parts that will be hereinafter more fully described and claimed and illustrated in the accompanying drawings in which:

Fig. 1 is a plan view of my improved laundering apparatus in position upon a bath tub.

Fig. 2 is a vertical section taken on the line 2—2 of Fig. 1.

Fig. 3 is an elevational view of the parts seen looking in the direction indicated by the arrow 3 in Fig. 2.

Fig. 4 is an enlarged detail section taken through the center of the bath tub or cover and showing the clothes rack supporting

rod in folded position on top of said lid or cover.

Fig. 5 is an enlarged detail section taken on the line 5—5 of Fig. 1.

Referring by numerals to the accompanying drawings, 10 designates an ordinary bath tub having the usual hot and cold water connections 11 and the upper marginal flange 12.

My apparatus includes a lid or cover plate 13, preferably formed of sheet metal 60 and of size and shape as to entirely cover the tub 10.

Arranged on the under side of this lid or cover and at its edge is a gasket 14, preferably formed of rubber that is adapted to 65 lie directly on top of flange 12 and produce a substantially water tight joint.

Secured on top of lid 13, near its ends are transversely disposed T bars 15 and 16, the ends thereof projecting slightly beyond 70 the side edges of lid 13 and passing through apertures in said projecting ends, are the shanks of hooks 17 that are adapted to engage beneath flange 12 of the tub.

The upper portions of the shanks of these 75 hooks 17 are threaded and receive winged nuts and said hooks and nuts provide means for very firmly securing the lid on the bath tub.

When the lid is applied to the tub, access 80 may be had to the faucets F through a hand hole 19, that is normally closed by a removable plate 20 and the latter being provided with suitable clamping means.

Formed in lid 13 near the cross bar 16 85 is a relatively large opening 21 through which the articles to be laundered may readily pass and this opening is normally closed by a readily removable plate 22, having suitable fastening means.

A horizontally disposed clothes-carrying rack 23 of wire mesh or suitable reticulated material is arranged to reciprocate vertically within bath tub 10, the ends of said rack bearing on vertical guide rods 24 that 95 depend from lid 13.

Secured on top of the center of this rack 23 is a socket 25 that receives the lower end

of a vertically reciprocating rod 26, the upper portion of which passes through an aperture 27 in the center of lid 13.

The lower end of rod 26 is detachably secured to socket 25, by means of two pins or bolts 28 that pass through suitably formed apertures in said rod and socket. The arrangement just described permits the pins or bolts 28 to be manipulated, so that when the rack 23 is lifted into position immediately beneath lid 13, and socket 25 projects through aperture 27, the rod 26 may be folded or swung downward into a horizontal position directly on top of lid 13 as illustrated in Fig. 4.

This procedure is carried out when the apparatus is removed from the tub or packed for storage or transportation.

Detachably secured to T bar 16 is the lower end of a wringer frame 29, in which is arranged for rotation a pair of wringer rolls 30, that are geared together by pinions 31.

Arranged on a support 32 at one end of frame 29 is a small electric motor 33, the shaft 34 of which is extended and has bearing on said frame and loosely mounted on the extended portion of said shaft is a pinion 35 and a gear wheel 36, the latter meshing with the upper one of the pinions 31.

Pinion 35 meshes with a gear wheel 37 that is loosely arranged on the shaft of the upper one of the wringer rolls.

The hubs of pinion 35 and gear wheel 36 are provided with suitable clutch faces that are adapted to be engaged by corresponding clutch faces that are formed on the ends of a collar 38 and which latter is arranged to rotate with and slide lengthwise upon the motor shaft between the hubs of said pinion 35 and gear wheel 36.

Clutch collar 38 is arranged to be shifted from one position to another by a small hand lever 39 that is fulcrumed on a bracket 40.

Journalled in bearings that project outward from the sides of the wringer frame 29 is a rock shaft 41 and projecting outwardly from the center thereof is an arm 42, the outer end of which is connected by a link 43 to the upper end of rod 26.

An arm 44 projects from one end of the rock shaft 41 along side of gear wheel 37 and passing through a slot 45 in said arm and seated in said gear wheel is a wrist pin 46.

A brace 47 is secured to the end of the lid 13, adjacent to the T-bar 16, the upper end of said brace being connected to the upper central portion of frame 29 and the lower end of said brace being adapted to rest on the floor.

In the operation of my improved washing machine lid or cover 13 is placed on top of the bath tub and secured thereto by proper

manipulation of the hooks 17 and wing nuts 18.

The tub is partially filled with water and the articles to be laundered are placed on rack 23.

Plates 20 and 22 are now secured in position to close the openings 19 and 21 and hand lever is now manipulated to shift clutch collar 38 into engagement with the hub of pinion 35.

As motor 30 is started the shaft thereof drives clutch collar 38 that is engaged with pinion 35 and the latter drives gear wheel 37 that runs idly on the shaft of the upper wringer roll.

As gear wheel 37 is thus rotated, arm 45 having a slot and pin connection with said gear wheel will be vibrated vertically, thereby rocking shaft 41, and consequently swinging arm 42 through a vertical plane.

As a result of these movements, rack 23 will be reciprocated vertically and the clothes carried by said rack will be constantly agitated in the wash water, thereby accomplishing the cleansing operations in a relatively short time.

After the articles have thus been laundered, clutch collar 38 is moved to a neutral position so as to stop the clothes rack vibrating mechanism and after detaching plate 22 the laundered articles are removed through opening 21 and lifted so as to be engaged by and pass through the wringer rolls 30.

These wringer rolls are driven by shifting clutch 38 into engagement with the hub of gear wheel 36 and, as the latter is rotated, its motion is transmitted through pinions 30, to said rolls.

By removing the rack 23, rod 26 and wringer frame 29 from the lid and securing the latter in position on the tub a convenient bath cabinet is provided, whereby a person may take a steam or medicated vapor bath and in such case, the person using the tub enters and leaves the same through the opening 21.

Thus it will be seen that I have provided a relatively simple and practical apparatus that may be applied to an ordinary bath tub to form a convenient and effective household washing machine.

Obviously minor details in the size, form and construction of the various parts of my improved laundering apparatus may be made and substituted for those herein described without departing from the spirit of the invention, the scope of which is set forth in the appended claims.

I claim as my invention:

A household laundering appliance comprising a cover plate that is adapted to be detachably positioned on top of a bath tub, a clothes receiving rack mounted for vertical reciprocatory movement beneath the cen-

tral portion of said cover plate, guide rods depending from said cover plate, which guide rods provide bearings for the end portions of said vertically reciprocating rack, ¹⁵ there being a normally closed opening formed in that portion of said cover plate that is positioned over the faucets of the bath tub, and a normally closed opening formed in said cover plate above the clothes receiving rack, a post secured to one end of said cover plate, the lower end of which post is adapted to rest on the floor adjacent to the bath tub to which the cover plate is applied, and motor driven means mounted above one end of the cover plate for imparting reciprocatory movement to the clothes receiving rack.

In testimony whereof I affix my signature.

MAX BRANDT.
